(57) **CLAIM**

The ornamental design for an elf leg, as shown and described.

DESCRIPTION

FIG. 1 is a front perspective view of an elf leg, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The thin broken lines in the drawings illustrate the portions of the elf leg, which form no part of the claimed design.

The thick broken lines representing stitching are part of the claimed design.
